UNITED STATES PATENT OFFICE.

ERASTUS EWING, OF ALBANY, NEW YORK.

IMPROVEMENT IN CHAMBER TOILET-CASES.

Specification forming part of Letters Patent No. **156,213**, dated October 27, 1874; application filed September 12, 1874.

To all whom it may concern:

Be it known that I, ERASTUS EWING, of the city and county of Albany, State of New York, have invented certain useful Improvements in Chamber Toilet-Cases; and I do hereby declare that the following is a description thereof, reference being had to the accompanying drawings, forming a part of this specification, in which—

Figure 1 is a perspective view of the toilet-case, illustrating the improvements in the same when the parts are opened out. Fig. 2 is a perspective view of the same when closed. Fig. 3 is a sectional elevation of the same. Fig. 4 is a plan view of the same.

My invention relates to that class of toilet-cases combining a commode, washing facilities, towel-rack, and other devices for use in a chamber or room; and consists in the herein-after-described parts, combined and arranged in such a manner that the case may, when not in use, present a neat and compact article, capable of being opened out, in its several parts, for several uses incidental to chamber purposes, by any person prior to an appearance in the family.

To enable others skilled in the art to make and use my invention, I will proceed to describe it in reference to the drawings and the letters of reference marked thereon, the same letters indicating like parts.

In the drawings, A A, representing the case or cabinet, may be made with any desired form of outer appearance and ornamentation, and of wood or any other proper material. Made in one side of the said case, in the top portion of the same, is a water-tank, B, provided with a cover, b, capable of being raised. a is a jointed faucet, connecting with the said water-tank, and capable of being swung out from the case. C is a door, hinged to the said water-tank side of the case, and toward the rear of the same. Made secure to the said door is the wash-case D, consisting of the segmental wall e, provided with a door, e¹, inclosing the wash-bowl d in its upper portion, and affording room for a stop-water vessel, d', in its lower portion.

The said door C being thus placed, and carrying the wash-case D and its adjuncts, is capable of transferring the same to within the case or cabinet A when the door is swung shut, and out from the same when it is opened, while the water-tank and faucet may be employed to supply the wash-bowl with water as may be required.

Made with the opposite side of the said case A is a second door, E, hinged in a manner similar to door C. Made with, or secured to, the said door is the commode-case F, provided with a door, e, and a seat, e¹, inclosing a bowl, pan, bucket, e², or equivalent vessel, to be used with the seat as a commode. The said door, with its adjuncts, is capable of being closed into the case A, as shown by dotted lines in Fig. 3, when the commode-case and its vessel will be completely hidden. Secured to the side of the case within, and directly over the seat e when closed in, is a stationary sealing-cover, f, which may have its edges or lower surface packed with rubber or felt cloth, to operate as a packing, to tightly close the commode-case when turned within the case A, as shown in Figs. 2 and 3.

If desired, an earth-box may be provided, with suitable devices for supplying the vessel in the commode-case with earth.

In the front of the case A is made a shallow chamber, g, closed by the door G, to which door is secured the towel-rack g', from which towels may be suspended.

H is a drawer, made in the upper portion of the case A. I is a mirror, supported in a swinging manner from proper standards h h. In cheaper articles I would dispense with the said mirror. J J are boxes for holding any articles necessary to be used for toilet purposes, which boxes may also be dispensed with in cheap articles.

By the improvements in this invention a single case may be made to supply all the articles for accommodation of a private toilet, and conveniences for comfortable and neat operations, while all escape of odors to the room, or from the commode to the other parts, is prevented.

Having described my invention, what I claim, and desire to secure by Letters Patent, is—

1. In combination with the case A, the water-tank B, provided with the faucet *a*, and the wash-case D, holding the vessel or vessels *d d'* carried by the side door C, substantially as and for the purpose set forth.

2. In combination with the case A and the commode-case F, carried by the door E, the sealing-cover *f*, substantially as and for the purpose set forth.

ERASTUS EWING.
